Fig. 10

<img alt="Schematic diagram of the electrical system for the Wheel Motor, Attachment Motor, Wheelslide Motor, Table Motor, Coolant Pump Motor, and Headstock Motor. The diagram shows various components like resistors, switches, and solenoids, with component numbers like 130, 139, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 6610, 6611, 6612, 6613, 6614, 6615, 6616, 6617, 6618, 6619, 6620, 6621, 6622, 6623, 6624, 6625, 6626, 6627, 6628, 6629, 66210, 66211, 66212, 66213, 66214, 66215, 66216, 66217, 66218, 66219, GRINDING MACHINE

Adrien E. Mandeville, Pawtucket, and Lester J. Lalime, Providence, R. I., assignors to Brown and Sharpe Manufacturing Company, a corporation of Rhode Island

Application August 28, 1942, Serial No. 456,484

9 Claims. (Cl. 51—115)

The present invention relates to improvements in grinding machines, and more particularly to an indexing mechanism for positioning different faces of the work successively for grinding.

It is an object of the invention to provide in a cylindrical type grinding machine, a novel construction and arrangement of the several cooperating instrumentalities of the machine suitable for the grinding of relief surfaces upon both faces of a milling cutter as composite parts of a complete grinding operation which the machine is set up to perform.

It is another object of the invention to provide a novel and improved indexing mechanism for imparting relative angular positioning movements to the grinding wheel assembly and work support which will operate automatically and with a high degree of precision to cause the work to be located in different angular positions with relation to the axis of rotation of the grinding wheel assembly for the performance of successive grinding operations upon different faces of the work.

The invention is herein disclosed as embodied in a grinding machine of the general type adapted for cylindrical grinding having a work supporting assembly including a longitudinally movable work table, a swivel support, and a headstock and footstock mounted thereon, a grinding wheel carriage movable toward and away from the work, and a rotatable grinding wheel spindle having its axis parallel to the line of movement of the work table.

In accordance with the invention, applicants provide a grinding wheel sleeve assembly comprising two oppositely faced disk grinding wheels spaced to receive the work piece therebetween, and an automatic indexing mechanism for indexing the swivel support and work mounted thereon between alternate positions in which one and then the other face of the cutter is brought into the correct angular relation to the adjacent grinding wheel for the performance of a relief grinding operation thereon.

The indexing mechanism herein disclosed as embodying certain features of the invention, comprises a pair of adjustable stops for limiting movement of the swivel support in each of its alternate indexed positions, and actuating mechanism acting automatically when rendered operative to shift the swivel support from one to the other stop-engaging indexed position. In the preferred form of the invention, the actuating mechanism comprises a crank which is arranged to be rotated through successive half revolutions,

and a yieldable connection between the crank and the swivel support which is rendered operative by the rotation of the crank to hold the swivel support under a firm engaging pressure against each stop in turn. The automatic mechanism referred to, comprises an electric motor which is connected to rotate the crank, a starting switch connection under the control of the operator for starting the motor, and a dog actuated limit switch rendered operative at the end of each half revolution of the crank to disconnect the motor.

Further in accordance with the invention, a simple and efficient form of yielding connection is provided between the crank and the swivel support which takes the form of a telescopic rod having two relatively movable telescoping links and a spring-actuated control device for maintaining the links yieldably in predetermined relation to one another. The spring-actuated control device referred to, comprises a compression spring mounted in a cylindrical chamber formed between the inner and outer link and arranged to be seated at its opposite ends against shouldered portions associated with each of the inner and outer links, so that any tendency of the telescoping links to move relatively toward or away from each other from a predetermined intermediate position will be resisted by the pressure of the spring.

The several features of the invention consist also in the devices, combinations and arrangement of parts hereinafter described and claimed, which together with the advantages to be obtained thereby will be readily understood by one skilled in the art from the following description taken in connection with the accompanying drawings, in which Fig. 1 is a perspective view of the work supporting and grinding wheel assemblies of a grinding machine, illustrating particularly applicants' table indexing mechanism; Figs. 2 and 3 are detail views partly in section, showing the work in the two alternative positions with respect to the grinding wheel assembly for the performance of the two face relieving operations upon a milling cutter; Fig. 4 is a detail view in front elevation of the bracket on the swivel support connecting with the telescoping rod of the indexing mechanism; Fig. 5 is a sectional view looking from the right, of the upper portion of the machine, illustrating particularly the indexing mechanism including the telescopic connecting rod; Fig. 6 is an enlarged detail view partly in section, illustrating particularly a bracket mounted on the swivel support and form-

ing parts of the indexing mechanism, together with the stops for limiting movement of the support about its swivel in each direction; Fig. 7 is a detail sectional view taken on the line 7—7 of Fig. 5; Fig. 8 is a detail bottom plan view taken on the line 8—8 of Fig. 5; Fig. 9 is a somewhat fragmentary plan view of the grinding machine shown in Fig. 1, illustrating particularly the grinding wheel assembly, the work supporting assembly and the indexing mechanism; and Fig. 10 is an elementary electrical diagram of the machine.

Referring to the drawings, the cylindrical type grinding machine illustrated as embodying in a preferred form the several features of the invention, comprises a base 20 having supported thereon a work table 22 longitudinally movable on ways 24, and a swivel support 26 supported to turn on a pivot 28 on the table 22. Mounted on the swivel support 26 is a motor driven headstock unit 30 and a footstock unit 32, these parts being arranged to support between them a work piece in the form of a milling cutter 34 upon which a relief grinding operation is to be performed.

The illustrated machine is provided also with a grinding wheel spindle carriage 36 which is supported to move in a horizontal plane transversely toward and away from the work. The carriage 36 provides support for a grinding wheel spindle indicated in dotted lines at 38 in Fig. 5, a grinding wheel spindle driving motor 40, and a belt driving connection 42. The illustrated machine is provided with a pair of oppositely faced disk grinding wheels 44, 46 which are supported on a sleeve mounting 48 secured to the spindle 38. The grinding wheels 44, 46 are spaced from one another a distance sufficient to permit the work piece as, for example, the milling cutter 34, to be interposed therebetween and to be manipulated for the performance of the relief grinding operations as hereinafter more fully set forth.

In accordance with the invention, applicants provide an indexing mechanism for swinging the swivel support between alternate positions in which the milling cutter 34 to be ground is brought to the desired angular position with respect to the grinding wheel 44, and then with respect to the grinding wheel 46 for the performance of relief grinding operations upon the two faces of the milling cutter 34. The grinding wheels 44 and 46 are spaced from one another a sufficient distance to permit the swivel support 26 to be turned from one to the other position while the cutter is disengaged from both grinding wheels. After the swivel support and work piece supported thereon have been indexed to the desired position, the work table 22 is moved longitudinally to cause the work to be fed to depth with relation to the grinding wheel. The grinding wheel spindle carriage and grinding wheel assembly thereon, are maintained in their fully advanced position during the performance of the entire operation of grinding both faces of a work piece.

The mechanism for indexing the swivel support comprises a crank consisting of a disk 60, a crank pin 62 supported for adjustment radially thereon, and a telescopic connecting rod consisting generally of a link 64 pivotally supported on the crank pin 62, and a link 66 pivotally supported on a pivot pin 68 on a bracket 70 secured to the right hand end of the swivel support 26. In order to provide for adjustment in the length of the radius arm of the crank, the crank pin 62

is provided at its lower end with a squared head 80 which is fitted into an undercut slot 82 extending radially from the pivotal axis of the disk 60. The crank pin 62 is clamped rigidly in adjusted position by means of a clamping nut 84 which is screw-threaded to the upper end of the crank pin, and acts against a sleeve bearing 86 for the link 64 on the crank pin to force the same into clamping engagement with the upper surface of the disk 60.

The crank is arranged to be rotated through successive 180° increments of rotation, and acts through the yieldable connection provided by the telescopic rod as hereinafter more fully to be described, to cause the support to be moved yieldably against a stop in each of its alternate indexed positions to provide an accurate and dependable positioning of the swivel support and work support thereon in the desired angular position with relation to the axis of rotation of the grinding wheel for the relief grinding of the opposed faces of a milling cutter supported on the machine. As best shown in Figs. 5 and 6 of the drawings, the bracket 70 on the swivel support 26 is provided with a stop lug or plate 88 which is arranged for engagement with two adjustable stops 90 and 92 which take the form of blocks slidably supported in an undercut slot 94 extending across the upper face of the work table 22. The blocks are provided respectively with stop screws 96 and 98 for engagement with the stop plate 88.

The construction and arrangement of the yieldable connection provided between the crank pin 62 and bracket 70 on the swivel support 26 will be readily understood from an inspection of Fig. 5 of the drawings. As shown in this figure, the telescopic link 66 is bored to receive one end of a rod 100 which is pinned thereto. The other end of the rod 100 is fitted to slide within a cylindrical bore 102 formed in a sleeve member 104 screw-threaded into a bore in the end of the telescopic link 64. The telescopic links are maintained yieldably in predetermined relation to one another by means of a spring-actuated control device including a compression spring 106 coiled about the rod 100 between two collars 108 and 110 loose on the rod 100. The collar 110 which takes the thrust of the spring 106 in one direction, is arranged to bear against a shoulder 112 formed by the end of the enlarged bore 114 in the sleeve member 104 within which the spring 106 is housed, and also against a shoulder 116 formed by the end of the reduced stem portion of the shaft 100 on which the spring 106 is supported. The collar 108 which takes the thrust of the spring 106 in the opposite direction, is arranged to bear against a sleeve element 118 screw-threaded to the shaft 100 and held in place thereon by a locking nut 120. The collar 108 bears also against an inwardly flanged portion 122 of a sleeve 124 screw-threaded to the outer end of the sleeve member 104, so that the sleeve 124 and sleeve member 104 are connected to move as a unit with the telescopic link 64. A locking screw 126 serves to lock the sleeve 124 in adjusted position on the sleeve member 104. With this construction and arrangement of the cooperating parts, it will readily be seen that the telescopic links 64, 66 are normally maintained yieldably in an intermediate position in which the collar 110 is engaged with both of the abutments 112, 116, and the collar 108 is engaged with the end of the sleeve element 118 and with the inwardly flanged portion 122 of sleeve 124.

In operation, movement of the disk 60 and crank pin 62 rearwardly to the one of its alternate positions shown in Fig. 5, causes the connected end of the swivel support 26 to be moved rearwardly. The lug 88 is thus brought into engagement with the stop pin 98, causing the link 64 to be extended slightly with respect to the link 66 as the crank pin 62 comes to rest in the limiting position shown. This extending movement of the telescopic link 64 causes the inwardly flanged portion 122 of sleeve 124 and collar 108 to be moved correspondingly to the right toward the collar 110, which is prevented from endwise movement by engagement with the inner shoulder 116 on rod 100 forming a part of telescopic link 66. This relative movement of the collars 108 and 110 tends to compress the spring 106 so that the swivel support 26 and lug 88 are held yieldably but firmly in engagement with the stop pin 98.

During the next succeeding 180° rotational movement of the disk 60 and crank pin 62, the swivel support is moved to its alternate position in which the lug 88 is engaged against the stop screw 96 and the telescopic links 64 and 66 are relatively compressed against the pressure of spring 106 to maintain the swivel support firmly in said alternate position. Compression of the spring 106 in this instance is caused by movement of the shouldered portion 112 of sleeve element 104 and collar 110 engaged thereby to the left toward collar 108 which is prevented from endwise movement by engagement with the sleeve nut 118 on the relatively stationary telescopic link 66 and rod 100.

It will be understood that adjustment of the effective pressure of spring 106 is obtained by adjustment of the position of the sleeve nut 118 on shaft 100, and by a corresponding adjustment of the position of sleeve 124 on sleeve member 104. Adjustment of the length of the telescopic rod as a whole may be readily obtained without varying the pressure on the spring by rotating the sleeve member 104 to move the same axially with respect to the telescopic link 64 having screw-threaded engagement therewith. During said latter adjustment, the sleeve 124 will be turned as a unit with the sleeve member 104, these parts being held against relative movement by means of the locking screw 126.

In the preferred construction illustrated in the drawings, the crank disk 60 is arranged to be driven through successive half revolutions by means of an electric motor 130 and a reduction gear unit connecting the motor with the disk. As indicated in dotted lines in Fig. 5, the drive is taken from the armature shaft 132 of the motor through gears 133, 134, 135, and 136 to a pivot shaft 137 on which the crank disk 60 is rigidly secured. A mechanical braking unit generally indicated at 138 which may be of well known construction, is provided for mechanically braking the motor to a stop when electrically disconnected.

Further in accordance with the invention, electrical operating connections are provided which are responsive to the operation of a starting button to start the motor 130, and thereafter act automatically to disconnect the same when the armature 132 and crank disk 60 have turned through 180°. The electrical control devices for this purpose comprise a manually operable start button 138, a manually operable stop button 140, a limit switch 142, a limit switch actuating lever 144, and trip dogs 146 and 148 which

are supported in an annular slot 150 formed in the under face of the crank disk 60. The switch lever 144 is supported on a pivot 152 and is provided at its outer end with a roll 154 for engagement with the dogs 146 and 148. As best shown in the elementary wiring diagram Fig. 10, the motor 130 there referred to as the attachment motor, is arranged to be energized by means of a solenoid actuated switch AR. The pressing of the start button 138 will close the starting contacts 77-78 to energize the solenoid AR for starting the motor 130. AR contact 79-78 closes forming a holding circuit to maintain the solenoid AR energized. At the end of a half revolution of the crank disk 60 and crank pin 62, one of the dogs 146, 148 will be brought into engagement with the roll 154 to rock the switch actuating lever 144, thus opening contact 77-79 to de-energize the solenoid AR and stop the attachment motor 130. At the same time contact AR 78-78 opens, so that the motor remains stopped.

It will be understood that the invention is not limited to the specific embodiment shown, and that various deviations may be made therefrom without departing from the spirit and scope of the appended claims.

What is claimed is:

1. In a cylindrical type grinding machine having a grinding wheel assembly arranged for the grinding of different faces of the work, a rotary grinding wheel spindle, a rotary work support, and a swivel support movable between alternate indexed positions to alter the angular relation of the grinding wheel spindle and work holder axes for the performance of successive face grinding operations on each of said different faces, and an indexing mechanism comprising power means, a manually operable starting control, connections rendered operative by the actuation of said control to render said power means operative to shift said swivel support from one to the other of said alternate positions, and a limit control responsive to the movement of the support to either of said alternate positions to render said power means inoperative.
2. In a cylindrical type grinding machine having a grinding wheel assembly arranged for the grinding of different faces of the work, a rotary grinding wheel spindle, a rotary work support, and a swivel support movable between alternate indexed positions to alter the angular relation of the grinding wheel spindle and the work holder axes for the performance of successive face grinding operations on each of said different faces, and an indexing mechanism comprising stops for positively limiting swinging movement of said swivel support in each of said positions, power actuating means including a yieldable connection for engaging and supporting the swivel support against the associated stop in each indexed position, and means under the control of the operator for rendering said power actuating means operative to index the support.
3. In a cylindrical type grinding machine having a grinding wheel assembly arranged for the grinding of different faces of the work, a rotary grinding wheel spindle, a rotary work support, and a swivel support movable between alternate indexed positions to alter the angular relation of the grinding wheel spindle and the work holder axes for the performance of successive face grinding operations on each of said different faces, and an indexing mechanism comprising stops for positively limiting angular movement of the swivel

support in each of said positions, a crank and a yieldable connection therefrom with the swivel support constructed and arranged for each successive half revolution of the crank to shift and to yieldably engage the swivel support against the associated stop in each alternate index position, and means under the control of the operator for rotating said crank through successive half revolutions.

4. In a cylindrical type grinding machine having a grinding wheel assembly arranged for the grinding of different faces of the work, a rotary grinding wheel spindle, a rotary work support, and a swivel support movable between alternate indexed positions to alter the angular relation of the grinding wheel spindle and the work holder axes for the performance of successive face grinding operations on each of said different faces, and an indexing mechanism comprising stops for positively limiting angular movement of the swivel support in each of said positions, a crank and a yieldable connection therefrom with the swivel support constructed and arranged for each successive half revolution of the crank to shift and to yieldably engage the swivel support against the associated stop in each alternate indexed position, an electric motor and connections therefrom for rotating the crank, a starting switch for the motor, a limit switch, and dogs associated with the crank for actuating the limit switch to stop the motor at the completion of each successive half revolution of the crank.

5.. In a cylindrical type grinding machine having a grinding wheel assembly arranged for the grinding of different faces of the work, a rotary grinding wheel spindle, a rotary work support, and a swivel support movable between alternate indexed positions to alter the angular relation of the grinding wheel spindle and the work holder axes for the performance of successive face grinding operations on each of said different faces, and an indexing mechanism comprising stops for positively limiting angular movement of the swivel support in each of said positions, a crank, a telescopic rod connecting the crank with the swivel support, said telescopic rod comprising telescoping links, and means connecting said links tending to maintain said links yieldably against relative movement from a position of predetermined length of said rod either into or away from each other, said crank and telescopic rod being constructed and arranged for each successive half revolution of the crank to shift and to yieldably engage the swivel support against the associated stop in each alternate indexed position, and means under the control of the operator for rotating said crank through successive half revolutions.

6. In a cylindrical type grinding machine having a grinding wheel assembly arranged for the grinding of different faces of the work, a rotary grinding wheel spindle, a rotary work support, and a swivel support movable between alternate indexed positions to alter the angular relation of the grinding wheel spindle and the work holder axes for the performance of successive face grinding operations on each of said different faces, and an indexing mechanism comprising stops for positively limiting angular movement of the swivel support in each of said positions, a crank, a telescopic rod providing a yieldable connection between the crank and the swivel support, said telescopic rod comprising telescoping links having formed in the telescoping portions thereof superimposed shouldered cylindrical recesses of equal length, a coiled compression spring housed

within the space formed by said recesses and arranged at each end to act against the recessed shoulders of both links, said crank and telescopic rod being constructed and arranged for each successive half revolution of the crank to shift and to yieldably engage the swivel support against the associated stop in each alternate indexed position, and means under the control of the operator for rotating said crank through successive half revolutions.

7. In a cylindrical type grinding machine having a grinding wheel assembly arranged for the grinding of different faces of the work, a rotary grinding wheel spindle, a rotary work support, and a swivel support movable between alternate indexed positions to alter the angular relation of the grinding wheel spindle and the work holder axes for the performance of successive face grinding operations on each of said different faces, and an indexing mechanism comprising stops for positively limiting angular movement of the swivel support in each of said positions, a crank, a telescopic rod providing a yieldable connection between the crank and the swivel support, said telescopic rod comprising an inner link having a shouldered portion and an axially adjustable collar spaced therefrom to form a shouldered recess of adjustable length, an outer link having a sleeve member secured to and axially adjustable with relation to the outer link for receiving the inner link, said sleeve member having formed therein a shouldered portion overlying the shouldered portion formed on the inner link, and a sleeve axially adjustable on the sleeve member and having an inwardly flanged end portion overlying said collar to provide a shouldered recess of adjustable length on the outer link, a compression spring coiled about the inner link in the space provided by said recesses and arranged for engagement at each end against the shoulders associated with both the inner and outer links, and means under the control of the operator for rotating said crank through successive half revolutions.

8. In a cylindrical type grinding machine, the combination of a base, a longitudinally movable work support, a work table, a swivel support mounted thereon, and a rotary work holder on the swivel support, a grinding wheel support and a grinding wheel spindle having supported thereon a grinding wheel assembly arranged for grinding different faces of the work, and means for indexing the swivel support between alternate positions for the performance of the grinding operation on each of said different faces comprising stops for positively limiting rotational movement of the swivel support in each of said alternate positions, a crank, a telescopic rod connecting the crank and the swivel support, said crank and connecting rod being constructed and arranged for movement in excess of that required to move the swivel support between said positions, spring means tending to maintain the connecting rod at a predetermined length, a motor and reduction gearing therefrom for rotating the crank, a starting switch for the motor, and control means for disconnecting the motor following each succeeding half revolution of the crank to move the swivel support from one to the other of said positions.

9. In a cylindrical type grinding machine having a grinding wheel assembly arranged for the grinding of different faces of the work, a rotary grinding wheel spindle, a rotary work support, and a swivel support movable between alternate

indexed positions to alter the angular relation of the grinding wheel spindle and work holder axes for the performance of successive face grinding operations on each of said different faces, and an indexing mechanism comprising an electric motor and braking means associated therewith, and connections from the motor including a crank for oscillating the support between

5 said alternate indexed positions, a starting switch for the motor, a limit switch rendered operative by movement of the support to either indexed position, and connections rendered operative by said switch to disconnect the motor and set the brake.
